HINGE CONSTRUCTION

Filed Aug. 25, 1928

UNITED STATES PATENT OFFICE.

JULIUS RITTER, JR., OF RACINE, WISCONSIN, ASSIGNOR, TO HARTMANN TRUNK COMPANY, OF RACINE, WISCONSIN, A CORPORATION OF WISCONSIN.

HINGE CONSTRUCTION.

Application filed August 25, 1928. Serial No. 301,975.

This invention relates to improvements in hinge construction, and more particularly to a hinge construction for hand luggage, trunks and the like.

5 Wardrobe cases or containers of a certain type are formed of two hingedly connected sections adapted to open with respect to each other, so that one section, when open, extends horizontally to lie flush on the floor or a support. If the ordinary metal hinges are used, the same form external protuberances which prevent the perfectly flat disposition of the one section of the case.

10 It is, therefore, one of the objects of the present invention to provide a non-metallic leather hinge construction for luggage in which the hinge portions do not protrude from the luggage and are flush with the surfaces thereof, permitting the flat disposition 20 of one section when open.

A further object of the invention is to provide a leather hinge construction for luggage, eliminating the necessity for any metal parts in the hinges and thereby materially 25 increasing the lightness of the luggage.

30 A further object of the invention is to provide a hinge construction for luggage or cases, which, when the case sections are closed, provides a rounded edge harmonizing in appearance with the other edges of the case, whereby the hinges are concealed, and giving to the case a neat and attractive appearance.

35 A further advantage of the leather hinge construction resides in the fact that the case may be constructed with very thin veneer board for lightness, which board would not ordinarily permit the attachment of metal hinges.

40 A further object of the invention is to provide a hinge construction for wardrobe cases in which the veneer boards of the case, the hinge strips and the outer leather covering may all be joined by stitching.

45 A further object of the invention is to provide a leather hinge construction which is very simple, is strong and durable, and is well adapted for the purposes described.

With the above and other objects in view, the invention consists of the improved hinge 50 construction, and its parts and combinations, as set forth in the claims, and all equivalents thereof.

In the accompanying drawing in which the same reference characters indicate the 55 same parts in all of the views:

Fig. 1 is a vertical sectional view of an opened wardrobe case illustrating the improved hinge construction joining the two 60 sections of the case;

Fig. 2 is an enlarged fragmentary detail sectional view showing adjacent portions of the case in open position and the hinge construction;

Fig. 3 is a similar view showing the portions of the case sections closed with respect to each other and the corresponding disposition of the hinge portions;

Fig. 4 is a fragmentary side view of the 70 wardrobe case when closed; and

Fig. 5 is an enlarged fragmentary detail view of a hinge portion and the stitching therefor.

Referring now more particularly to the drawing, it will appear that the numeral 8 75 indicates a wardrobe case having a wardrobe section 9 with a right angular lower extension 9', and a compartment section 10 hingedly connected to the end portion of the extension section and adapted to open and 80 close with respect to the wardrobe section.

The body portion of each case section is formed of thin sheets or strips of veneer board 11 covered on the inner surface by a fabric lining material 12 and covered on the 85 outer surface by leather 13 or the like. The corner edges of the case sections are of a rounded construction, as indicated at 14.

The inner edge of the bottom portion of the compartment section 10 is joined to the 90 outer edge of the bottom portion of the extension 9' by the improved hinge construction. The adjacent edge portions of the sections 9' and 10 are of a rounded reinforced construction with the veneer sheets 11 95 rounded and covered externally with round-

ed veneer strips 15 and 16 respectively. The improved hinge construction is formed by an elongated strip 17 of leather or other strong flexible material, which as arranged, is substantially S-shaped in cross-section when the case sections are open with respect to each other, as shown in Figs. 1 and 2. Said hinge strip 17 is glued to the inner surface of the lower veneer board 11 of the 10 section 9' and is then extended between the adjacent edges of the veneer boards 11 and strips 15 and 16 of the sections 9' and 10 and over the outer or lower surface of the strip 15. The leather covering 13 extends over 15 and covers the outer portion of said hinge strip. There is also an auxiliary inner flexible strip 18 covering the inner portion of the hinge strip and secured to the inner edge portion of the veneer board 11 of the section 10.

Due to the hinge construction described, the veneer boards of the case may be comparatively thin and lines of stitching, indicated at 19, are run through and join the 25 outer leather covering 13, the veneer boards 11 and strips 15 and 16, the hinge strip 17 and the auxiliary inner strip 18. The lining material 12 covers the entire interior of the case sections and is held in place by glue 30 or a like adhesive medium, said lining material covering the hinge strip and auxiliary strip, as shown.

It will thus be seen that the improved hinge construction provides a light and 35 simple non-metallic hinge connection between a pair of luggage sections. When the sections are opened, the hinge strip is extended in the S formation shown in Fig. 2, while when the sections are closed, the hinge 40 strip and adjacent layers of material fold as shown in Fig. 3, with the bunched material accommodated in the space between the adjacent edge portions of the sections. When the case is closed the edge portion of the 45 same which is hinged (that at the left in Fig. 4), is rounded and is substantially similar in appearance to the other edge portions of the case. When the sections of the case are opened, a flat disposition of the same is 50 permitted, as there are no projecting rigid hinge parts.

From the foregoing description it will be seen that the improved hinge construction for wardrobe cases, luggage and the like, is 55 both simple and novel, and is well adapted for the purposes set forth.

What is claimed as the invention is:

1. The combination with a pair of case sections, each having a rigid wall, of a hinge 60 strip connecting a pair of adjacent edge portions of said sections, consisting of an elongated flexible strip secured to the inner surface of the wall of one section and then extended between said adjacent edges of said

sections and secured to the outer surface of 65 the wall of the other section.

2. The combination with a pair of open ended case sections disposed with their open ends adjacent each other, the walls of said sections being rigid, of a hinge connection 70 for the adjacent end portions of said sections, consisting of an elongated flexible strip overlapping the adjacent edge portions of said sections and extending transversely thereof and secured to the inner surface of 75 the wall of one section and to the outer surface of the wall of the other section with its intermediate portion extended between the adjacent edge portions of said walls.

3. The combination with a pair of open ended case sections disposed with their open ends adjacent each other, the walls of said sections being rigid and being covered with sheets of material both internally and externally, of a hinge connection for the 80 adjacent end portions of said sections, consisting of an elongated flexible strip overlapping the adjacent edge portions of said sections and extending transversely thereof and interposed between the inner surface of 85 the wall of one section and its internal covering and also interposed between the outer surface of the wall of the other section and its external covering, with its intermediate 90 portion extended between the adjacent edge 95 portions of said walls.

4. The combination with a pair of open ended case sections disposed with their open ends adjacent each other, the walls of said sections being rigid and being covered with 100 sheets of material both internally and externally, of a hinge connection for the adjacent end portions of said sections, consisting of an elongated flexible strip overlapping the adjacent edge portions of said sections and extending transversely thereof and interposed between the inner surface of the wall 105 of one section and its internal covering and also interposed between the outer surface of the wall of the other section and its external covering, with its intermediate portion extended between the adjacent edge portions of said walls, and a common securing 110 means extending through the external covering of said sections, the rigid walls thereof and the flexible hinge strip.

5. The combination with a pair of open ended case sections disposed with their open ends adjacent each other, the walls of said sections being of veneer and covered internally and externally with sheets of material, of a hinge connection for the adjacent end portions of said sections, comprising 120 an elongated flexible strip overlapping the adjacent edge portions of said sections and extending transversely thereof and interposed between the inner surface of the veneer of one section and the inner covering 125

therefor and also interposed between the outer surface of the veneer of the other section and its outer covering, with its intermediate portion extended between the adjacent edge portions of said walls, an auxiliary flexible strip secured over the inner portion of said first-mentioned flexible strip and also secured to the inner surface of the

veneer of the adjacent section, and stitching passed through the outer covering, the adjacent veneer walls of both sections, the first-mentioned flexible strip, and the auxiliary flexible strip.

In testimony whereof, I affix my signature.

JULIUS RITTER, JR.
